Fig. 6.

FIG. 1 is a top plan view of a food warming tray showing my new design wherein the top surface is unornamental;

FIG. 2 is a front elevational view thereof;

FIG. 3 is a bottom plan view thereof;

FIG. 4 is a perspective view thereof;

FIG. 5 is a top plan view wherein the top surface is provided with ornamentation denoting a weathered wood grain; and

FIG. 6 is a top plan view wherein the top surface is provided with ornamentation denoting a close wood grain.

The essential features of my design reside in the configuration of the tray disclosed in the drawings.

The end and side opposite those shown are substantially identical to those shown except for the omission from the opposite end of the power cord receiving socket.

I claim:

The ornamental design for a food warming tray, as shown and described.
